UNITED STATES PATENT OFFICE.

ROBERT A. BROOKS, OF CHICAGO, ILLINOIS.

FLUSHING-VALVE.

No. 876,518.

Specification of Letters Patent.

Patented Jan. 14, 1908.

Application filed April 23, 1906. Serial No. 313,153.

To all whom it may concern:

Be it known that I, ROBERT A. BROOKS, a citizen of the United States, and a resident of the city of Chicago, in the county of Cook 5 and State of Illinois, have invented certain new and useful Improvements in Flushing-Valves; and I do hereby declare that the following is a full, clear, and exact description of the same, reference being had to the 10 accompanying drawings; and to the letters of reference marked thereon, which form a part of this specification.

This invention relates to improvements in flushing valves of that class set forth in my 15 prior application for patent for flushometers, filed December 4th, 1903, Serial No. 183,790, and in which a manually operated flushing valve is adjusted to close automatically after a regulable period of discharge in flushing.

20 In various flushing valves the same fluid that is used in flushing acts also to close the valve. These are frequently out of order because of sediment in the water closing or partly closing the necessary passages for regulation with the result that the valve fails to operate properly, if at all. Where other fluids are used for regulating the valve closing the evaporation of the fluid or leakage may in some cases affect the regulation.

25 With these objections in view the object of the invention is to afford a positively operating flushing valve adapted to give full opening instantaneously when actuated and to close slowly as regulated against pressure and 30 without hammering after a regulable period of discharge.

It is also an object of the invention to afford a cheap, simple and durable construction and one not likely to get out of order 40 through long continued use.

It is a further object of the invention to provide a construction wherein the regulation of the valve is pneumatically controlled.

The invention consists in the matters herein 45 after described and more fully pointed out and defined in the appended claims.

In the drawings: Figure 1 is a central vertical section of a device embodying my invention showing the valve closed. Fig. 2 is 50 a similar view showing the valve just after the same has been actuated to open the valve. Fig. 3 is a section taken on line 3—3 of Fig. 1. Fig. 4 is a section taken on line 4—4 of Fig. 1. Fig. 5 is a section taken on line 5—5 of Fig. 2. Fig. 6 is a top plan view of the movable valve.

As shown in said drawings: referring first to Figs. 1 and 2, A, indicates the valve casing provided at its lower end with an inlet pipe a , and a laterally directed outlet pipe a' , which is threaded for engagement with the usual pipe connections. Said casing is cylindric in its interior and is provided at its bottom with a flat shoulder a^2 surrounding the inlet orifice, upon which is secured an annular 60 packing a^3 which may be of fiber or any suitable material and the aperture of which corresponds with the inlet aperture of the casing. At its upper end said casing is provided with an inwardly directed peripheral rib, a^4 65 the inner face of which is concentric with the casing and upon which is secured a packing ring a^5 . Above the packing ring a^5 the casing is internally threaded.

Fitted within the casing A with its upper 70 end fitting closely within the peripheral rib a^4 , and of a length to fit between the packing ring a^3 and a^5 is a cylindric shell A' which is open at its bottom and top and provided as shown with a transverse partition a^6 below 75 its middle and through which is provided a discharge aperture providing a downwardly facing valve seat. Said shell above said partition is provided with apertures opening into the discharge casing and to the outlet 80 passage a' .

Slidably secured in the upper end of the shell is a hydraulic head, comprising a piston B, of metal or other suitable material and having secured thereon a hydraulic packing 90 b , with the edges turned upwardly and which is secured in place by a washer b' as shown in Figs. 1 and 2. Said piston is provided on its lower end with an integral concentric boss b^3 of slightly less diameter than the discharge 95 aperture through said partition and which is adapted to project therethrough when the valve is forced downwardly, and as shown an axial tubular stem b^4 , integral therewith extends downwardly and is of a length for the 100 end thereof to extend into the inlet opening when the bottom of said piston B is forced within a short distance of the partition. Said stem is screw threaded externally and a valve closure is provided thereon comprising a relatively large washer b^5 at the lower end of 105 said stem above which is secured a packing washer b^6 , of sufficient size to fit to the seat and close the aperture through said partition a^6 and upon said packing washer is secured 110 a smaller washer b^7 which is of a smaller size than said aperture through said partition.

Said piston and the washer b' are provided with an axial chamber open at the top and which communicates with an axial passage extending downwardly through the boss b^3 , 5 and stem b^4 . Extending downwardly through said passage and connected with an enlarged head b^8 , in said chamber is a stem b^9 provided with a valve closure b^1 at its lower end closing the passage therethrough and affording 10 a vent valve.

Threaded in the upper end of the valve casing and bearing on the packing a^5 is a cylinder C provided at its upper end with internal screw threads as shown in Figs. 1 and 15 2 and provided with an integral bottom c having a central aperture therethrough and also having in its bottom a close fitting packing washer c' . A hollow cap C' which is threaded in the top of said cylinder closes the 20 upper end and as shown is provided at its lower end with external screw threads on which is threaded an annular clamping band c^3 , as shown in Figs. 1 and 2. This clamping band rigidly engages a hydraulic or pneumatic washer c^4 , and the upwardly directed and outwardly flanged edges of a rubber or other resilient pneumatic bag c^5 against the bottom of said cap. The bottom of said bag when extended reaches nearly to the bottom 25 30 of said cylinder and at all times rests upon and is secured to the flat head C^2 within said cylinder which is provided with a downwardly directed boss c^7 , which when the bag is fully open bears against said packing in the bottom of the cylinder. Threaded axially into said boss is a rod c^8 , the lower end of which is threaded into the head b^8 on the stem b^9 of the vent valve. A spring c^9 bears on said packing and on the under side of said 35 40 head C^2 and holds the bag normally in its closed position. Extending axially through said cap C' and into the bag is a tubular stem c^{11} , which as shown is provided at its lower end with a flat foot piece c^{12} threaded thereon 45 which bears against the bottom c^6 of the bag on its inner side and as shown said stem is provided with a very small vent port opening therewith closely above the foot piece and is also provided with an adjustable needle 50 valve c^{13} at a point slightly above the bottom or floor of said hollow cap and a port is provided in the stem at or near the seat of said valve. As shown the stem is provided with a very small bore at its lower end and a much 55 larger bore at its upper end and threaded therein is the adjustable needle c^{13} which can be thus regulated to a nicety to control the escape of air from said bag. As shown a port is provided through the piston B and 60 carried upon the rod or stem c^8 is a washer b^{16} , which when the stem is forced downwardly seats to close said port and also is elevated above the same when the flushing valve is closed.

65 The operation is as follows: With the

valve closed as shown in Fig. 1 downward pressure on the stem c^{11} first forces the vent valve open and the water flowing upwardly through the passage in the stem and piston creates pressure above the piston immediately forcing the valve downwardly to the position shown in Fig. 2. Should the stem be held down as sometimes occurs by those not familiar with these devices or by those meddling, instead of flushing continuously 70 the seating of the valve on the packing washer a^2 closes the valve and no water will flow. If now the stem is released the upward pressure on the valve from below is more than balanced by the downward pressure above the piston B and the valve would remain permanently closed on this lower seat were it not that the action of the spring b^9 , which gradually forces the air out of the bag c^5 and closes the vent valve thus cutting 75 off pressure from above the piston. Inasmuch as the adjustment of the vent valve with respect to the head b^8 , is such that when the vent valve is closed said head projects above the piston the closure of said vent valve necessarily raises the valve plate b^{16} thus venting the water, otherwise trapped above the piston, through the piston and into the chamber, in the lower end of the shell. Inasmuch as the bottom of the piston never 80 85 seats upon the partition a^6 a free passage is thus afforded to the outlet. In consequence the pressure above the piston is reduced and pressure from below gradually raises the valve and piston, the raising thereof being at all times regulated by the upward movement of the bottom of the pneumatic bag. For 90 obviously should the piston rise sufficiently to open the vent valve the conditions previously existing would be immediately restored either wholly or in part to check further upward movement until the bag has 95 sufficiently collapsed to allow further closure. The flushing valve finally closes and seats upon the partition in the shell A' at which 100 time the vent valve being closed by the pressure of the spring c^9 thereon the valve remains permanently closed until actuated. 105

Obviously the rate of closure can be perfectly regulated by regulating the escape of air from the pneumatic bag or cylinder and this is accomplished by means of the needle valve or any suitable arrangement of valves for the purpose. It is desirable however to permit said bag to fill quickly in actuating 115 the flushometer to start the flow and for this purpose, as shown, the floor of the plug or cap C' is provided with a relatively large opening therethrough and the packing washer c^4 , is provided with downwardly 120 turned edges at its center and which bear against said stem, serving as a valve to afford quick and full opening when the stem is forced inwardly in actuating the valve.

Obviously while I have described the 130

mechanisms as pneumatically controlled, it may be controlled by any suitable fluid in pneumatic bag or chamber. I do not purpose limiting this application for patent otherwise than necessitated by the prior art as various details of construction may be varied without departing from the principles of my invention.

I claim as my invention:

1. In a flushometer the combination with a casing affording a water chamber, of an inlet and an outlet pipe connected therewith, a valve seating automatically to close the inlet pipe, a manually operated vent valve acting to start the flow whereby the automatic valve is unseated and means operated by fluid other than the flushing fluid for controlling the closing of both the vent valve and automatic valve.
2. In a device of the class described the combination with a casing having an inlet and an outlet, a partition dividing said casing into a plurality of chambers, an automatically closing valve adapted to seat on one side of the partition to close the communication between the inlet and outlet, a passage connecting opposite sides of the automatically closing valve, a manually unseated vent valve adapted to close the same, fluid controlled means regulating the rate of closing of said vent valve and a spring adapted to aid in closing the automatic valve.
3. In a device of the class described the combination with the outlet, and an inlet pipe of a manually opened valve seating automatically to close the inlet pipe at either of two limits of travel and a passage opening therethrough, a vent valve controlling said passage and fluid controlled means for regulating the closing of the vent valve in said closure.
4. In a device of the class described the combination with a casing having an inlet and an outlet pipe of chambers therein, a piston in one of said chambers, a stem extending downwardly therefrom into a lower chamber, a closure on the end of said stem to close the inlet, a passage through the piston, stem and closure affording communication between the inlet and above the piston, a normally seated vent valve for said passage adapted when unseated to admit pressure above said piston to open the closure, a passage through the piston approximately parallel with the aforesaid passage, a closure above the piston adapted to close said passage to automatically move the piston in one direction by inlet pressure and means movable with the vent valve adapted to automatically unseat said closure above the piston prior to seating the inlet closure.
5. In a device of the class described the combination with a casing having an inlet and an outlet orifice, a partition affording a valve seat, a piston movable above the parti-
- tion, a stem engaged thereto projecting beyond said partition, a closure thereon controlling the inlet, a plurality of passages through said piston, one extending through the stem and closure, a manually unseated vent valve opening one of said passages to admit inlet pressure above the piston, a valve adapted to close the other passage by inlet pressure and means automatically seating said vent valve and simultaneously unseating the valve controlling the other passage.
6. The combination with a casing having a water chamber therein having an inlet and an outlet of a fluid containing cup movable above the water chamber, a stem extending externally the casing and also into the water chamber, a closure for the inlet passage to said water chamber, a passage opening therethrough, a vent valve carried on said stem and controlling said passage, a spring acting normally to seat the closure said fluid containing cup connected with and controlling the closure of said valves.
7. In a flushometer the combination with a casing affording a water chamber of an inlet and an outlet pipe opening thereto and therefrom, an axial sleeve supported in said water chamber, above the inlet pipe, a partition dividing the same transversely, a passage opening axially through said partition and affording a valve seat on the under side thereof, an inlet valve closure normally closing the inlet passage, a restricted passage opening through said closure, a vent valve seating to close the same, a stem extending axially through the casing and said closure and engaging the vent valve, a spring normally holding the closure seated and a fluid containing cup movable on said stem and retarding the seating of the closure after flushing.
8. A flushing valve comprising a water casing having an inlet opening in its bottom and an outlet in its side, a sleeve fitting closely in said water casing and divided transversely by a centrally apertured partition, discharge apertures opening through said sleeve above the partition, a valve closure seating to close the partition and also seating at the top of the inlet opening and having a vent valve opening therethrough, a stem extending through said casing and engaged on the vent valve closure and adapted to be manually actuated, in unseating both valves and a collapsible cup connected on said stem and retarding closing of said valve.
9. In a flushing valve the combination with the valve controlling the flow of means for manually opening the same, mechanism acting to close the same and a collapsible cup containing fluid for controlling the rate of closure.
10. In a device of the class described the combination with a casing having an inlet and an outlet, a valve seat in the casing, a

- closure therefor, a piston rigidly connected therewith, a passage through the piston and closure, a vent valve normally closing the passage, manually operated means opening the 5 passage admitting inlet pressure above the piston to unseat the closure, fluid controlled automatically acting mechanism adapted to seat the vent valve and a valved passage through the piston opened simultaneously as 10 the vent valve closes permitting inlet pressure to seat said closure.
11. In a device of the class described the combination with a casing of an inlet and an outlet therefor, a valve seat in the casing between 15 the inlet and the outlet, a piston in said casing, an inlet closure connected therewith adapted to seat on said seat, a plurality of passages opening through the closure and a valve controlling each passage adapted to 20 alternately close its respective passage to vary the pressure on either side the piston thereby closing and opening the inlet controlling valve.
12. In a device of the class described the combination with a casing of an inlet and an outlet pipe therefor, a partition provided with a passage therethrough, a valve seat on one side of said partition, a differential valve closure normally seated thereon, a valve controlled passage through said closure, manually actuated means opening said passage, automatic means moving the closure from 30 said valve seat toward the seat on the inlet pipe when said passage is open and fluid controlled means regulating the return of said closure.
13. In a device of the class described the combination with a casing of an inlet and an outlet therefor, a seat in the casing, a piston movable above the same, a closure connected therewith, means admitting inlet pressure on the piston to unseat the closure by inlet pressure, means automatically closing said admission means and a valved passage automatically opened to release pressure from the 40 piston adapting inlet pressure to seat the closure.
14. In a device of the class described the combination with a casing having an inlet and an outlet orifice, a valve seat at the inlet orifice, a valve seat above said inlet valve seat, a valve closure movable by inlet pressure from above and beneath to seat said closure on said seats a vent valve adapted to 50 admit and cut off inlet pressure above said closure and regulable means controlling the rate of movement of the vent valve in one direction.
15. In a device of the class described the combination with a casing of an inlet and an outlet pipe therefor, a seat thereon, a closure adapted to seat thereon, a chambered cap secured on the casing, a flanged clamping ring secured thereto, a pneumatic bag

clamped between the same and said cap, a 65 hydraulic washer secured between the bag and cap adapted to admit air into the bag in opening and to close to prevent escape of air in closing the bag, regulable means permitting the air to escape from the bag to regulate the rate of collapsing thereof and operative connections between the bag and closure for regulating the rate of seating of the closure.

16. In a device of the class described the combination with a casing of an inlet and an outlet pipe therein, a plurality of aligned valve seats in said casing, a closure normally seated on one by inlet pressure and adapted to seat on the other at its opposite limits of movement to close said inlet pipe to prevent waste of the flushing fluid and a fluid controlled vent valve controlling the movement of the closure.

17. In a device of the class described the combination with a casing of an inlet and an outlet pipe thereon, a valve seat in said casing, a closure seated thereon by inlet pressure, a seat adjacent the inlet pipe, said closure seating thereon to prevent waste of the flushing fluid when moved to its lowest limit of movement a vent valve for said closure admitting inlet pressure to hold the closure unseated when opened and pneumatic means controlling the rate of closing of said vent valve.

18. In a device of the class described the combination with a casing of an inlet and an outlet pipe therefor, inwardly facing seats in said casing, a valve closure adapted to seat on either by inlet pressure to close the inlet pipe, a vent valve for admitting inlet pressure above the closure and pneumatic means controlling the rate of movement in one direction of both the valve closure and vent valve.

19. In a device of the class described the combination with a casing of an inlet and an outlet pipe opening thereinto, and therefrom, valve seats in said casing, a valve closure adapted to seat on either seat to close the inlet pipe, a normally closed and manually opened vent valve adapted to admit pressure above the closure for unseating the same and spring actuated and pneumatically controlled means governing the rate of movement of the closure and the rate of closing of said vent valve.

20. In a device of the class described the combination with a casing of an inlet and an outlet pipe therefor, valve seats in said casing, a valve closure adapted at one limit of movement to seat on one and to seat on the other at the opposite limit of movement to close the inlet, a normally closed vent valve controlling the side of the closure upon which inlet pressure is exerted, manual means for opening the same and pneumati-

ically controlled means regulating the upward movement of said closure and the closing of the vent valve.

21. In a device of the class described the combination with a casing of an inlet and an outlet pipe therein, alined valve seats in said casing, a valve closure normally seated on one of the same to close the inlet, a vent valve adapted when actuated to admit inlet pressure to move said closure toward the opposite seat and a bag manually operated in one direction and pneumatically controlling the rate of return movement of said closure and the rate of closing of the vent valve.

22. In a device of the class described the combination with a casing of an inlet and an outlet pipe therefor, valve seats in said casing, a valve closure normally seated on one of the same, means adapted to admit inlet pressure above the closure to move the same toward the other seat, a valve controlled passage automatically opened to release pressure from above the closure and collapsible pneumatic means controlling the period of flushing and the rate of opening of said passage.

23. In a device of the class described the combination with a casing of an inlet and an outlet pipe therefor, a valve seat adjacent the inlet orifice, a valve seat in axial alignment therewith, a differential valve closure held seated on one seat by inlet pressure, manually operated means admitting inlet pressure on the larger area of the closure to move the same toward the inlet orifice, a valve controlled passage for releasing inlet pressure on the larger area whereby inlet pressure returns the closure to the first seat, means automatically opening said passage and means controlling the rate of opening thereof.

24. In a device of the class described the combination with a casing having an inlet and an outlet of a plurality of valve seats therein, a differential closure adapted to seat on either to close the inlet, means admitting inlet pressure on the larger area to move the closure toward one seat, a valve automatically opened simultaneously as the admitting means is closed to release the pressure to move the closure to the other seat and pneumatic regulating means controlling the period of movement of the closure in one direction and the rate of movement of the pressure admission means and said valve.

25. In a device of the class described the combination with a casing having an inlet and an outlet, alined inwardly facing valve seats therein, a differential valve closure adapted to seat on either, a valve manually operated to admit inlet pressure to the larger area of said closure at one limit of movement and pneumatically controlled to cut off inlet pressure therefrom at the oppo-

site limit and a valve automatically actuated by movement of the aforesaid valve to release pressure from above the closure thereby moving said valve closure to close the inlet at each limit of movement by inlet pressure.

26. In a flushometer the combination with a casing provided with an inlet and an outlet pipe, a valve seat at the inlet pipe, a valve seat opposite the outlet pipe, a valve closure normally seated on the last named valve seat and held to its seat by inlet pressure from beneath, a vent valve admitting pressure above the closure to seat the same on the inlet valve seat and to hold said closure seated as long as the flushometer is manually actuated and a release valve relieving pressure from above the closure and automatically actuated simultaneously as the vent valve closes.

27. In a device of the class described the combination with a casing having an inlet and an outlet, a valve seat at the inlet, a valve seat at the outlet, a differential valve closure adapted to seat on either to close the inlet and held in either position by inlet pressure and independent valves one adapted to release inlet pressure to unseat the closure the other to seat the closure, said valves simultaneously movable and regulable means controlling the rate of movement of both of said valves.

28. In a device of the class described the combination with a casing having an inlet and an outlet orifice, a valve seat in the casing, a piston movable above the seat, a closure connected with the piston for said seat, a plurality of valve controlled passages through the piston, one of which extends through the closure, manually operated means for actuating the valve controlling one of said passages to unseat said closure and means automatically unseating the valve controlling the other passage prior to seating said closure.

29. In a flushometer the combination with a casing of an inlet and an outlet pipe therefor, a plurality of valve seats, a valve closure adapted to seat on either to close the inlet by inlet pressure, a vent valve admitting pressure above the closure and adapted to close to cut off the pressure, a relief simultaneously actuated as the vent valve closes to release pressure from above said closure and collapsible means regulating the period of flushing and the rate of closing of the vent valve.

30. In a device of the class described the combination with a casing of an inlet and an outlet pipe therefor, a plurality of valve seats, a valve closure normally seated on one adapted by inlet pressure from above to seat on the other seat and held seated thereon a predetermined time by inlet pressure above, a vent valve cutting off inlet pressure from

above, a valve simultaneously opened releasing pressure above the closure whereby inlet pressure moves the closure to normal and means regulating the seating thereof 5 and the rate of movement of both of said valves.

31. In a device of the class described the combination with a casing having an inlet and an outlet orifice, a valve seat in said 10 casing, a piston slideable above the seat, a downwardly extending stem integral therewith, a closure adjustable on the lower end of said stem, a passage through the piston and stem, a rod extending therethrough having 15 a head on the upper end thereof, an adjustable vent valve on the lower end of the stem adapted to close said passage, a passage extending through the piston, a valve adapted to close the same and unseated by said head, 20 a collapsible bag above the piston, means connecting the bag rigidly with the head and a stem extending into and rigidly connected to the bottom of the bag adapted when depressed to open the bag and the vent valve 25 to permit inlet pressure to open the closure and said closure automatically seated against pneumatic pressure.

32. In a device of the class described the combination with a casing provided with an 30 inlet and an outlet pipe of a valve seat therein, a differential closure for said seat, passages in said closure one affording communication between the inlet and above the closure, the other affording communication 35 between the outlet and above the closure and a valve for each passage adapted one to close its passage when the other opens its passage thereby seating and unseating the differential closure.

40 33. In a flushometer the combination with a casing of an inlet and an outlet pipe therefor, a valve seat in the casing, a closure automatically moved to and firmly held seated on one seat by inlet pressure and 45 moved to and held seated a predetermined time on another seat by inlet pressure above

if the flushometer is manually actuated for a considerable time thereby preventing the waste of the flushing fluid, an automatically operated valve for releasing the pressure 50 from above the closure and means controlling the rate of movement thereof.

34. A flushometer comprising a casing having inlet and outlet pipes, a valve seat at each, a closure normally held seated on one 55 by inlet pressure, moved toward the other by inlet pressure and returned to its normal position by inlet pressure a collapsible cup above the closure, a head rigidly secured to the bottom thereof, a stem extending into and rigidly engaged to the cup, a pneumatic washer rigidly secured to the top of the cup and adapted to admit air into the bag between the same and stem and to firmly close against the stem to prevent escape of air, 60 operative connections between the head and closure, a passage in the stem communicating within and outside the cup and means regulating the escape of air therethrough.

35. In a device of the class described the 70 combination with a casing of an inlet and an outlet pipe therefor, a valve seat near each, a closure normally seated on one seat by inlet pressure from beneath, manually operated means to admit inlet pressure above said 75 closure to move the same to the other seat and to hold the same seated as long as said manual means are actuated, automatically operated means cutting off inlet pressure from above the closure when said manual 80 means are released and a valve automatically actuated thereby releasing pressure above the closure adapting inlet pressure from beneath to return the same to normal.

In testimony whereof I have hereunto 85 subscribed my name in the presence of two subscribing witnesses.
